UNITED STATES PATENT OFFICE.

CHARLES E. BENNETT, OF TOPEKA, KANSAS.

WINDOW-SHADE BRACKET.

No. 874,655.

Specification of Letters Patent.

Patented Dec. 24, 1907.

Application filed July 25, 1907. Serial No. 385,542.

To all whom it may concern:

Be it known that I, CHARLES EMRIC BENNETT, citizen of the United States, residing at Topeka, in the county of Shawnee and State 5 of Kansas, have invented certain new and useful Improvements in Window-Shade Brackets, of which the following is a specification.

The present invention aims to provide a 10 novel device for adjustably mounting window shades and relates more particularly to that type of shade supporting devices comprising vertical guide ways having movable brackets adjustably mounted thereon.

15 The object of the invention is to design a vertically adjustable bracket of this character which is peculiarly formed so as to be readily moved up and down upon the guides and locked in any adjusted position thereon.

20 For a full description of the invention and the merits thereof and also to acquire a knowledge of the details of construction and the means for effecting the result, reference is to be had to the following description and 25 accompanying drawings, in which:

Figure 1 is a perspective view showing the shade support applied to a window frame. Fig. 2 is a horizontal sectional view through the same. Fig. 3 is an enlarged side elevation of one of the movable brackets. Fig. 4 is a transverse sectional view on the line 4—4 of Fig. 3. Fig. 5 is a vertical sectional view through one of the movable brackets showing the antifriction rollers. Fig. 6 is a detail 30 view of one of the movable brackets and a portion of the corresponding guide bar, the bracket being shown in the position assumed when passing the intermediate brace for the 35 guide bar.

40 Corresponding and like parts are referred to in the following description and indicated in all the views of the drawings by the same reference characters.

Specifically describing the present embodiment of the invention the numerals 1—1 designate the guide bars one of which is located upon each side of the window frame, the said guide bars having their ends secured to posts 2 projecting from the window frame. It will 50 be observed that the inner faces of the bars 1 are toothed as indicated at 3 and that the extremities of the said bars are shown as received within mortises formed in the extremities of the posts 2. In the present instance braces 4 are shown as reinforcing intermediate portions of the rack bars 1, the

extremities of the braces being formed with the laterally extending arms 5 projecting inwardly and secured to the outer sides of the bars 1. Slidably mounted upon the rack 60 bars 1 are the movable brackets 6 which support the shade roller 7. Each of the movable brackets 6 carries a pinion 8 meshing with the toothed portion 3 of the corresponding rack bar 1, and a pair of antifriction rollers 9 engaging the outer edge of the said rack bar. The two pinions 8 are connected for simultaneous movement by means of a shaft 10 and it will be readily apparent that by rotating the shaft and turning the pinions 8 the 65 movable brackets 6 can be vertically adjusted 70 upon the bars 1.

For the purpose of operating the shaft 10 a reel 11 is keyed upon the same or otherwise made rigid therewith adjacent one of the 75 brackets 6, the said reel being designed to receive an operating cord 12 and being provided upon its periphery with the teeth 13. Mounted upon the movable bracket 6 adjacent the reel 11 is a pawl 14 designed to engage the teeth 13 to lock the reel against 80 turning and a pendent arm 15 is formed in connection with the pawl, the said arm loosely engaging the operating cord 12. The weight of the arm 15 normally serves to 85 move the pawl 14 into engagement with the teeth 13, while upon grasping the cord 12 and swinging the same outwardly the arm 15 is swung about its pivot and the pawl 14 moved away from the teeth 13. The movable bracket 6 can then be raised by pulling 90 upon the cord 12 and unwinding the same from the spool 11, or lowered by letting out the operating cord 12 and permitting the same to wind upon the reel as the brackets 95 fall by gravity. When the movable brackets have been properly positioned the cord 12 is released and the arm 15 thereby permitted to swing downwardly and again throw the pawl 14 into engagement with the teeth 13. 100

Each of the movable brackets 6 is in the nature of a casing provided with an undercut groove 16 loosely receiving the corresponding rack bar 1, the mouth of the groove being designed to receive the inwardly projecting 105 arms 5 of the brace 4 when the bracket is moved past the said brace. The casings constituting the brackets 6 are provided with the removable plates or coverings 17 projecting slightly over the mouth of the groove 110 16 and normally held in position by means of fastening members such as the screws 18.

Attention is directed to the fact that owing to the provision of the antifriction rollers 9 engaging the rear faces of the rack bars 1 the movable brackets are caused to slide freely 5 upon the latter and all binding movement is eliminated.

Having thus described the invention, what is claimed as new is:

1. In a device of the character described, 10 the combination of a rack bar, means for supporting the rack bar, a bracket movable upon the rack bar, a pinion carried by the bracket and engaging the rack bar, a reel and cord for actuating the pinion, and means for locking the reel against movement, the said locking means being controlled by the before mentioned cord.

2. In a device of the character described, 20 the combination of a rack bar, means for supporting the rack bar, a bracket movable upon the rack bar, a pinion carried by the bracket and engaging the rack bar, a reel and cord for actuating the pinion, a pawl for locking the reel against movement, and an arm carried by the pawl and loosely engaging the cord.

3. In a device of the character described, 30 the combination of a rack bar, end posts supporting the rack bar, an intermediate brace provided with a lateral arm engaging the rack bar, a movable bracket provided with an under-cut groove receiving the rack bar, the mouth of the groove being designed to

receive the arm of the brace when the bracket is moved past the brace, and a pinion carried by the bracket for meshing with the rack bar.

4. In a device of the character described, the combination of a guide bar, a bracket movable upon the guide bar, means for sliding the bracket upon the guide bar, a reel mounted upon the bracket and controlling the means for sliding the same upon the guide bar, a cord co-operating with the reel, and a pawl engaging the reel for locking the same against movement, the said pawl being controlled by the cord.

5. In a device of the character described, the combination of a rack bar, a bracket 50 slideable upon the rack bar, a pinion journaled upon the bracket and engaging the rack bar, a reel for actuating the pinion, the said reel being provided upon its periphery with teeth, a gravity pawl normally engaging the teeth to lock the reel against movement, a 55 cord co-operating with the reel, and an arm carried by the pawl and loosely engaging cord to throw the pawl into an operative position when a pull is exerted upon the cord.

In testimony whereof I affix my signature 60 in presence of two witnesses.

CHARLES E. BENNETT. [L. S.]
